UNITED STATES PATENT OFFICE.

WALTER E. YOUNG, OF SYRACUSE, NEW YORK.

BELT BUCKLE.

Application filed November 13, 1922. Serial No. 600,572.

To all whom it may concern:

Be it known that I, WALTER E. YOUNG, of Syracuse, in the county of Onondaga, in the State of New York, have invented new and useful Improvements in Belt Buckles, of which the following, taken in connection with the accompanying drawings, is a full, clear, and exact description.

This invention relates to a buckle for trousers supporting belts which are usually passed through a series of loops in the waist band with sufficient clearance between the loops at the front to permit the free manipulation and adjustment of the buckle.

15 The belt is of course, more or less pliable or flexible and is therefore, free to sag more or less at the loops as well as between the loops due partially to the weight of the trousers and to the various movements of the 20 body of the wearer, and unless some means is provided at the center front of the band, that unsupported portion of the trousers will usually sag more than other portions to such an extent that the front of the belt will often 25 slide above the adjacent portions of the waist band.

In order to overcome this objectionable result, various devices have heretofore been proposed including a loop at the center front 30 of the band for engagement with tongue on the buckle and while this is efficient to a considerable degree it is not sufficient to prevent partial sagging or relative displacement of the center front portions of the waist 35 band and buckle owing to the fact that the downward strain of the loop upon the tongue is either at or below the longitudinal center of the buckle.

The main object of my present invention 40 is to provide the loop attaching element of the buckle near the upper edge thereof or at least above the longitudinal center, and near the upper edge of the waist band where it is more efficient in preventing downward 45 displacement of the waist band or upward displacement of the buckle, and at the same time preventing the upper edge of the waist band from turning down under the buckle.

Another object is to provide a more convenient means for attaching the front loop of the waist band to the buckle either before or after the belt has been tightened and clamped in place for the buckle, and also to prevent accidental displacement of the loop 55 from the buckle when the belt is adjusted for use.

Other objects and uses relating to specific parts of the buckle will be brought out in the following description.

In the drawings:

Figure 1 is an inner face view of the buckle showing by dotted lines, the adjacent portions of the belt and attaching loop on the center front of the trousers.

Figure 2 is a longitudinal sectional view taken on line 2—2, Figure 1.

Figures 3 and 4 are transverse vertical sectional views taken respectively on lines 3—3 and 4—4, Figure 1.

As illustrated, this buckle comprises a metal plate —1— having its opposite longitudinal edges overturned to one side of the main body partially across the rear face thereof toward each other to form opposed upper and lower flanges —2— and —3— and intervening grooves —4— between said flanges and main body for receiving and guiding one end of a belt A, the other end of which is secured to a loop —5— on one end of the plate —1—.

The upper flange —2— is wholly above the longitudinal center of the buckle and main body of the plate —1— and is provided with a lengthwise slot —6— substantially midway between its inner and outer edges and also substantially midway between the ends of the flange —2—, for receiving a loop —a— on the band B of the pair of trousers, said slot being opened at one end, thereby forming a tongue —7— on the lower edge of the flange —2—.

The free end of the tongue —7— is offset upwardly at —8— partially across the open end of the slot to form a passage —9— of less width than the remaining portion of the slot to permit the entrance of the loop —a— into said slot and around the tongue —7—.

The portion of the flange —2— at the open end of the slot —6— is preferably offset downwardly at —10— to form a shoulder extending part way across the slot and together with the upwardly offset portion —8— of the tongue —7— serving to restrain the loop —a— from sliding off from the tongue when the belt is adjusted for use upon the band of the trousers.

It is now evident that by placing the slot —6— and tongue —7— in the upper flange —2— near the upper edges of the band of the trousers and belt above the longitudinal center of the buckle and substantially mid-

way between the ends of the buckle not only prevents the slightest sagging of the center front of the upper edge of the trousers but also prevents the adjacent portion of the belt and buckle from slipping above the trouser band, and also prevents the upper edge of the trouser band from rolling inwardly and downwardly.

That is, by placing the slot and tongue 10 near the upper edge of the buckle, enables the trouser band and buckle to lie flatwise against the body and assures a more perfect alinement with the upper edge of the front portion of the belt with the 15 upper edge of the adjacent portion of the trousers all which contributes material to the carrying out of the main object of the invention.

The loop —5— is hinged by pintles —11— 20 to the upper and lower sides of the plate —1— in close proximity to the flanges —2— and —3— and is provided with a cam member —12— movable into and out of engagement with the belt A to hold the latter in 25 its adjusted position in the buckle.

I claim:

1. A buckle for trouser supporting belts comprising a metal plate having a belt-attaching loop at one end and its opposite 30 longitudinal edges bent toward each other to form opposed flanges at the back of the

main body of the plate, one of said flanges being provided with a lengthwise slot open at one end to receive a loop on the trousers.

2. A buckle for trouser supporting belts 35 comprising a metal plate having a belt-attaching loop at one end and its opposite longitudinal edges bent toward each other to form opposed flanges being provided with a lengthwise slot open at one end to receive 40 a loop on the trousers, the open end of said slot being of less width than its remaining portions to facilitate the retention of the trouser loop in the slot.

3. A buckle for trouser supporting belts 45 comprising a metal plate having a belt-attaching loop at one end and its opposite longitudinal edges bent toward each other to form opposed flanges at the back of the main body of the plate, one of said 50 flanges being provided with a lengthwise slot open at one end to receive a loop on the trousers, a portion of the last named flange being offset laterally part way across said slot near the open end thereof to hold 55 the trouser loop in the slot.

In witness whereof I have hereunto set my hand this 9th day of November 1922.

WALTER E. YOUNG.
